UNITED STATES PATENT OFFICE.

WILLIAM S. LAMSON, OF LOWELL, MASSACHUSETTS.

STORE-SERVICE APPARATUS.

SPECIFICATION forming part of Letters Patent No. 292,928, dated February 5, 1884.

Application filed December 10, 1883. (No model.)

To all whom it may concern:

Be it known that I, WM. S. LAMSON, of Lowell, Middlesex county, Massachusetts, have invented certain Improvements in Store-Serv-
ice Apparatus, of which the following is a specification.

My invention relates to that class of store-service apparatus in which graduated carriers move upon ways between the main desk 10 and the stations; and my invention consists in automatic switch apparatus whereby any of the carriers, as desired, may be automatically directed from the main track to a branch track.

15 In the drawings, Figure 1 is a side view of sufficient of a store-service apparatus to show my improvement. Fig. 2 is a plan view; and Fig. 3 is a section on the line 1 and 2, looking in the direction of the arrow.

20 A is the main track, and B is the side track, which branches to one side to a point beneath the main track, and extends to one or more of the stations of the store. Sections *a* of the main-track rail are connected together to form a switch, D, pivoted at *x*, so that the switch-rails remain normally in line with the track, in which case the carriers will pass along the main track; or the switch may be tilted to the position shown in dotted lines, 25

30 Fig. 1, in which case the carrier will be directed to the branch track B. In order that the switch thus formed may be operated automatically, I use any available appliance that will lock the switch-rail in one position, but

35 will be operated by carriers of a determined size or construction to unlock the switch and permit it to direct such carriers to the side track. One means which I have found to be practically effective is shown in the drawings, 40 and consists of a catch-lever, *b*, pivoted at one side of the track and catching under a lug or lip, *e*, of the switch to hold it in place, and an operating-lever, *h*, pivoted to a standard, *m*, at the side of the track, jointed to the catch- 45

lever *b*, and provided with an adjustable contact-pin, *i*. Carriers which pass freely below the pin *i* will not affect the position of the switch; but larger carriers that strike the pin *i* will lift the upper end of the lever *h* and

move the catch-lever to release the switch, 50 when the latter will fall under the weight of the carrier and will direct the latter to the branch track. It will be evident that there is no tendency of the carrier to leave the track as it operates the switch, the pin *i* tending 55 rather to keep it to the track, and the switch being operated by the momentum of the carrier alone and not by its gravity. The switch carries a counterbalance-weight, *s*, or is otherwise counterbalanced so as to recover its position when the carrier passes from it, the point of the lip *e* being beveled so as to force back the lever *b*, which then slips under the lug and holds the switch in place.

Without limiting myself to the precise construction of switch and operating devices shown, I claim—

1. In a cash-service apparatus having graduated carriers, the combination of a main track, branch track extending to stations of the store, 70 switch devices for locking the same in one position, and appliances arranged to be moved by the carriers to be switched and to thereby cause the switch to assume a position to direct the carriers onto the other track, substantially 75 as set forth.

2. The combination of the main track, side track, switch pivoted that it may be brought to coincide with either track, lock, and appliances whereby to unlock and change the position of the switch by the action of some of the carriers, while others are permitted to pass 80 onward upon the main line.

3. The combination, with the track of a store-service apparatus, of a pivoted switch-section, and locking device constructed to be operated by the momentum of special carriers to unlock said section and permit the same to move under the weight of the carrier, substantially as specified. 90

In testimony whereof I have signed my name to this specification in the presence of two subscribing witnesses.

W. S. LAMSON.
